US00D916693S

(12) **United States Design Patent** (10) **Patent No.:** **US D916,693 S**
(45) **Date of Patent:** **** Apr. 20, 2021**

(54) **CASE FOR PORTABLE ELECTRONIC DEVICE**

(71) Applicant: **SAMSUNG ELECTRONICS CO., LTD.**, Gyeonggi-do (KR)

(72) Inventors: **Jongdeuk Son**, Gyeonggi-do (KR); **Jinie Ryu**, Gyeonggi-do (KR); **Jaewoong Chung**, Gyeonggi-do (KR); **Hyounghsin Park**, Gyeonggi-do (KR)

(73) Assignee: **SAMSUNG ELECTRONICS CO., LTD.**, Gyeonggi-Do (KR)

(**) Term: **15 Years**

(21) Appl. No.: **29/716,320**

(22) Filed: **Dec. 9, 2019**

(30) **Foreign Application Priority Data**

Jun. 14, 2019 (KR) 30-2019-0028382

(51) LOC (13) Cl. **14-03**

(52) U.S. Cl.

USPC **D14/250**

(57) **CLAIM**

The ornamental design for a case for portable electronic device, as shown and described.

DESCRIPTION

FIG. 1 is a front perspective view of a first embodiment of case for portable electronic device, showing our new design;

FIG. 2 is a front view thereof;

FIG. 3 is a rear view thereof;

FIG. 4 is a left side view thereof;

FIG. 5 is right side view thereof;

FIG. 6 is a top plan view thereof;

FIG. 7 is a bottom plan view thereof;

FIG. 8 is a rear perspective view thereof;

FIG. 9 is a front perspective view of a second embodiment of a case for portable electronic device, showing our new design;

FIG. 10 is a front view thereof;

FIG. 11 is a rear view thereof;

FIG. 12 is a left side view thereof;

FIG. 13 is right side view thereof;

FIG. 14 is a top plan view thereof;

FIG. 15 is a bottom plan view thereof; and,

FIG. 16 is a rear perspective view thereof.

The broken lines in the figures depict portions of the case for portable electronic device that form no part of the claimed design.

1 Claim, 16 Drawing Sheets
